UNITED STATES PATENT OFFICE.

EDWARD F. NASSOIX AND GEORGE E. JOHNSON, OF SPARKS, NEVADA.

LANTERN ATTACHMENT.

1,413,486.

Specification of Letters Patent. Patented Apr. 18, 1922.

Application filed September 13, 1920, Serial No. 409,801. Renewed March 3, 1922. Serial No. 540,916.

To all whom it may concern:

Be it known that we, EDWARD F. NASSOIX and GEORGE E. JOHNSON, citizens of the United States, residing at Sparks, in the county of Washoe and State of Nevada, have invented new and useful Improvements in Lantern Attachments, of which the following is a specification.

This invention relates to lanterns, particularly to those used by railroad men for signaling and other purposes and has for its object the provision of an attachment for a lantern of this character adapted to replace the oil font and burner whereby to convert the lantern into an electrical lantern, the attachment being in the nature of a lantern containing a plurality of dry cells and having a socket carrying an incandescent bulb.

An important object is the provision of an attachment of this character which is constructed complete in itself and which may be slipped into the bottom portion of a railroad lantern after the oil burner and font thereof have been removed, the attachment being held in place by a holder engaging against the top thereof and against the top of the lantern.

Another object is the provision of a device of this character which has built thereinto a simple switch mechanism whereby the current may be turned on or off, as desired.

An additional object is the provision of a device of this character which will be simple and inexpensive in manufacture, easy to install, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a side elevation of the lantern,

Figure 2 is a vertical longitudinal sectional view,

Figure 3 is an elevation of our device detached and showing the parts assembled,

Figure 4 is a similar view showing the parts separated,

Figure 5 is a plan view of the lower part of the attachment,

Figure 6 is a perspective view of the battery.

Figure 7 is a perspective view of the means for holding the shell and battery within the base.

Figure 8 is a perspective view of the handle rod,

Figure 9 is a detail cross sectional view showing the switch device in elevation, and

Figure 10 is a horizontal sectional view taken through the switch device shown in Figure 9.

Referring more particularly to the drawings, the letter A designates the wire frame of the lantern which is shown as being of the well known type used by trainmen and others, and B designates the top, hinged as shown at C, and provided with a catch D for holding it closed. Depending from this top is the usual flange E. The letter F designates the handle which is connected with the frame A in the usual manner whereby to be either pivoted or to be locked rigidly. The letter G designates the base or bottom of the lamp which is secured within the lower portion of the frame A and which ordinarily contains the oil font and supports the burner. The oil font and burner are not shown as in carrying out the present invention they must be removed.

In carrying out our invention we provide a shell 10 which is formed as an inverted cup member and which is provided with an outwardly extending flange 11 adapted to seat upon the top of the base G. Formed in the center of the top of this shell is a socket 12 within which is screwed the shank of an incandescent bulb 13. Disposed within this shell is a battery 14 formed of any suitable number of dry cells connected, or it may be preferred to use a single large cell. This battery is enclosed within a protective casing 15 which may be of card-board or the like and within the upper end of which is disposed an upwardly spring-pressed plate 16 which is of course electrically connected with the cells to form one terminal. Located within one side of the casing 15 is a metallic strip 17 which forms the other terminal. This battery seats within the base G and is firmly engaged within the shell 10.

In order to prevent dislocation of this attachment we provide a disk 18 flanged, as shown at 19, and adapted to engage the flange E of the top B. Depending from this disk at diametrically opposite points are rods 20 which carry at their lower ends arcuate plates 21 which engage against the outside of the shell 10 and which engage the top of the flange 11 for holding the shell and battery firmly in position within the base

- G. The socket 12 carried by the shell extends through a central hole 22 in the top of the casing 15 and engages the spring-pressed plate 16.
- 5 The switch structure associated with the device comprises a block 23 of insulating material secured upon the inside of the shell 10. Secured upon this block is a leaf-spring 24 which when the parts are assembled engages the metallic strip 17. Secured transversely of this block 23 is a strip 25 and journaled through this strip and through the block and shell is a rod 26 having an angular end 27 serving as a handle. The spring 24 10 terminates in spaced relation to the strip 25. Secured upon the rod 26 is a contact arm 28 which is of course grounded on the shell and this contact arm is movable to engage the spring 24 so as to complete the circuit 15 20 through the bulb.

In the use of the device it will be seen that the battery is disposed within the base G with the shell 10 fitting upon the top thereof. These parts are held in position by an auxiliary frame including the disk 18, rods 20 and plates 21. When the rod 26 is turned to bring the arm 28 into engagement with the spring 24, the current will flow through and energize the incandescent bulb 13, as 25 30 will be obvious. When the use of the device is not desired, it is merely necessary to turn the handle 27 through an arc of ninety degrees, whereupon the current will be cut off and the lamp deenergized.

35 From the foregoing description and a study of the drawings it will be apparent that we have thus provided a simply constructed and consequently inexpensive device for transforming an oil lantern into an electrical lantern, the device being easily installed and being so simple as not to get out of order, as well as having the great advantage of not being subject to being blown out by wind or rain.

40 45 While we have shown and described the preferred embodiment of our invention it is of course to be understood that we reserve the right to make such changes in the form, construction, and arrangement of parts as

will not depart from the spirit of the invention or the scope of the subjoined claims.

Having thus described our invention, we claim:

1. In combination with a lantern including a frame, a cover hinged thereon, and a base designed for holding an oil font and burner; an attachment comprising a battery of cells located within said base, a shell engaged upon the upper end of the battery and fitting upon said base, a disk member 55 60 engaging against the underside of the top of the lantern, rods depending from said disk, and plates carried by the lower ends of said rods and engaging said shell whereby to hold said shell down.

2. In a lantern including a supporting frame and a base, an attachment replacing the oil font and burner ordinarily disposed within the base, the attachment comprising a battery of dry cells enclosed within a casing and fitting within the base, the top of the casing having a hole, a spring-pressed plate within the casing electrically connected with the battery to form one terminal thereof, a shell fitting upon said battery and seating 70 75 upon said base, a socket carried by said shell, projecting through said hole and engaging said plate, a bulb within said socket, and a switch mechanism carried by the shell and connected with the battery and the bulb 80 85 whereby to complete the circuit there-through, said switch mechanism comprising a metallic plate on the casing connected with the battery and forming the other terminal thereof, a block of insulating material secured within said shell a leaf-spring carried by said block and engaging said metallic strip, a cross strip on said block, a rod journaled through the shell, the block and the cross strip and having its outer end formed with a handle, and an arm on said rod movable to engage said spring, the rod, arm, and socket being grounded on the shell.

In testimony whereof we affix our signatures.

EDWARD F. NASSOYI.
GEORGE E. JOHNSON.
